By # UNITED STATES PATENT OFFICE.

CHARLES A. RUSSELL, JR., OF ORANGE, TEXAS.

BLOW-OUT PATCH.

1,334,171.

Specification of Letters Patent. Patented Mar. 16, 1920.

Application filed November 15, 1919. Serial No. 338,237.

To all whom it may concern:

Be it known that I, CHARLES A. RUSSELL, Jr., a citizen of the United States, residing at Orange, in the county of Orange and 5 State of Texas, have invented certain new and useful Improvements in Blow-Out Patches; and I do hereby declare the following to be a full, clear, and exact description of the invention, such as will enable 10 others skilled in the art to which it appertains to make and use the same.

This invention relates to new and useful improvements in patches for tires or shoes of the character which are placed between 15 the inner tube and a weak place or point in the shoe to prevent blow-outs and has for one of its objects the provision of means for preventing the tube from being pinched or injured by the device.

20 Another object of this invention is the provision of means for securing the edges of the patch or body thereto in overlapping relation and about the tube, thereby rendering a complete inclosure for the tube at the 25 weak point or place of the shoe and also prevent the patch from sliding or shifting in relation to the tube and shoe while the device is in use.

A further object of this invention is the 30 provision of a body so constructed that old fabrics from worn shoes or tires can be used in partially constructing the same, thereby reducing the cost of manufacture of the device and further the body is provided with 35 means to prevent pinching of the tube at the ends of said body.

A still further object of this invention is the provision of a patch of the above stated 40 character, which shall be simple, durable and efficient, and which may be manufactured and sold at a comparatively low cost.

45 With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawings, in which—

50 Figure 1 is a fragmentary longitudinal sectional view of a pneumatic tire illustrating a patch applied thereto and constructed in accordance with my invention,

Fig. 2 is a plan view illustrating my preferred form of fastening means,

Fig. 3 is a transverse sectional view illustrating the tube surrounded by the patch, 60

Fig. 4 is a plan view of the patch disposed flatly or in an open position,

Fig. 5 is a detail sectional view taken on the line 5—5 of Fig. 4,

Fig. 6 is a sectional view taken on the line 65 6—6 of Fig. 4,

Fig. 7 is a transverse sectional view, 70 illustrating a modified form of fastening means,

Fig. 8 is a fragmentary plan view of the 75 edges of the body secured together by male and female fastening elements.

Referring in detail to the drawings, the numeral 1 indicates as an entirety the body 80 of a patch and is constructed from inner and outer layers of fabric 2 and 3. The outer layer of fabric 3 is preferably constructed from new material while the inner layer of fabric 2 may be constructed from old fabric taken from shoes or tires that are 85 partially worn out, thus reducing the cost of manufacturing the body. Placed between the edges of the layers of fabric 2 and 3 is rubber 4 which projects beyond the edges of said layers of fabric to provide 90 95 pliable edges to the body to prevent pinching of an inner tube when using the body between the tube 5 and the shoe 6. The rubber and layers of fabric are secured together by a well known process of vulcanizing.

A flap 8 is formed integrally with one edge of the body 1 by extending the outer layer of fabric 3, and this tongue is adapted to overlap the other edge of the body 95 when said body is assembled about a tube as illustrated in Fig. 3. The flap 8 besides being constructed from a continuation of the outer layer of fabric 3, may have an inner layer of fabric 9 vulcanized or otherwise 100 secured to the outer layer to form the flap of considerable strength. The flap is provided with eyelets 10 preferably three in number to receive a lacing cord 11. The lacing cord 11 is placed between the inner 105 and outer layers of fabric prior to the vulcanizing operation and is extended through openings in the outer layer 3 to form loops 12 and tying ends 13. The tying ends are arranged in close proximity to each other 110 and between the loops and said loops are adapted to be passed through the end eye-

- lets in the flaps, while the tying ends are adapted to be passed through the intermediate eyelets and after the loops and tying ends have been passed through their respective eyelets, the tying ends are then passed through the loops and tied together thereby firmly securing the flap to the body and in an overlapping position, so that a continuous protector is provided for the inner tube.
- 10 The patch is applied to the inner tube prior to placing the tube in the shoe and preferably when the tube is in a partially inflated condition. After the patch has been applied to the tube, said tube and patch are then placed into the shoe having the patch located at the weak point in the tire or shoe and the flap secured to the free edge of the body prevents the patch or body from sliding laterally on the tube thereby keeping
- 15 the body in proper location in respect to the weak point in the shoe. The rubber 4 provides flexible ends to the body which will prevent said body from pinching the inner tubes.
- 20 Referring to my modified form of fastening means as shown in Fig. 7, a plurality of hooks 14 are secured to the edge of the body 1, and are adapted to engage in the eyelets 10 for the purpose of securing the
- 25 flap to the body.
- In Fig. 8 I have shown another modified form of means of securing the flap to the body in which female members 15 are secured to the body and are adapted to receive male members 16 carried by the flap.

While I have shown and described the preferred embodiment of my invention, it will be understood that minor changes in construction, combination, and arrangement of parts may be made without departing from the spirit and scope of the invention as claimed.

Having thus described my invention, what I claim is:—

1. A patch comprising a body, a flap formed on one edge of said body and adapted to overlap the other edge of the body and having eyelets therein, a lacing cord secured to the body and consisting of loops and tying ends adapted to be extended through the eyelets and have the ends of the cord passed through said loops and tied together.

2. A patch comprising a body including inner and outer layers of fabric secured together, a flap formed on one edge of said body and adapted to overlap the other edge and having eyelets, a tying cord positioned between the layers of the fabric and adapted to extend through the other layer of fabric in form of loops and tying ends, said loops and tying ends adapted to extend through the eyelets and the tying ends then passed through the loops and secured together.

In testimony whereof I affix my signature in presence of two witnesses.

CHARLES A. RUSSELL, JR.
